UNITED STATES PATENT OFFICE

HARRY J. HANSEN, OF LA JUNTA, COLORADO

CLOSURE LOCK

Application filed August 1, 1930. Serial No. 472,228.

This invention relates to closure locks and more particularly to locks for the caps upon motor vehicle gasoline tanks.

The main object of the invention is to provide an electromagnetically operated lock cap for automobile gasoline tanks which can only be operated or unlocked when the automobile ignition switch is turned on thus preventing unauthorized persons from removing the cap. 10 A further object is to provide a lock cap which may be applied to the tank without any alteration of the same whatever.

A further object is to provide a lock cap of the above characteristics in a simple, durable 15 and efficient form.

The foregoing and other objects together with means whereby the same may be carried into effect will best be understood from the following description of a preferred embodiment of the invention taken in connection with the accompanying drawings wherein:

Figure 1 is a cross section through the upper portion of the cap showing the locking 25 elements in plan.

Figure 2 is a section along the line 2—2 in Figure 1.

Referring now more particularly to the drawings, the reference character A designates a portion of the conventional gasoline tank and B the externally threaded annulus or neck thereon surrounding the mouth C through which the tank A is filled. The present invention comprises an attaching ring 30 1 and a cap 2 hinged at 3 to the said ring 1. The attaching ring 1 is internally threaded as shown at 4 and is so adapted to be screwed on the annulus B of the tank to support the cap 2 thereon. An inwardly extended lip 5 is provided on the ring 1 and the same overlies the end of the annulus B and a lug or ear 6 is depended from this lip 5 in spaced relationship to the inner threaded periphery of the ring 1 and diametrically opposite the hinge 3 whereby the said lip may slip within the annulus B as shown. A lock screw 7 is threaded through the lug 6 and serves as a means for rigidly securing the ring 1 on the annulus B as will be readily 45 understood. The cap 2 is hollow and has

its underside closed by a circular plate 8 whereby the cap is closed against the entrance thereto of gasoline which might be splashed from the tank A. An electromagnet 9 is mounted within the cap 2 and the same has its axis aligned with the hinge 3 and the point on the ring 1 to which the lug 6 is attached, the outer end of the said electromagnet being disposed adjacent the point at which the cap 2 is hinged. A partition 10 is extended 55 across the cap 2 within the plate 8 at right angles to the axis of the electromagnet 9 and at some distance from the inner end thereof. A lock plunger 11 is slidably mounted through an aperture 12 in the partition 10 in axial alignment with the electromagnet 9, the said plunger being square in cross section so that it cannot rotate as will be understood. An enlarged head 13 is provided on the inner end of the plunger 11 and an expansion coil spring 14 is braced between this head 13 and the electromagnet 9 whereby the plunger is normally urged outward away from the electromagnet. The head 13 of course limits this outward movement of the plunger 11. The spring 14 is seated over or around the extended core 15 of the electromagnet 9 and is so held in its 60 proper position. A locking catch 16 is extended upward from the lip 5 on the ring 1 above the lug 6 and extends into the cap 2 through an aperture 17 in the plate 8 thereon. Near its upper end the catch 16 has an aperture 18 to receive the end of the lock plunger 11 and the extreme upper end of the catch is bent or curved to one side as 65 shown at 19. The outer end of the plunger 11 is beveled off as shown at 20 and the arrangement is such that the plunger will first be forced inward toward the electromagnet 9 as the cap 2 is closed against the ring 1 70 by this beveled end 20 striking the curved end 19 of the catch 16, the plunger of course entering the aperture 18 when it comes in alignment with the same. An expansion coil spring 21 is seated in a recess 22 provided 75 in the ring 1 diametrically opposite the hinge 3 and this spring is compressed when the cap 2 is closed for a purpose to be described. A bushing 23 is provided through the cap 2 over the hinge 3 and the current 80

supply wires 24 and 25 of the electromagnet 9 pass out through this bushing and are connected to the source of electrical current in a manner to be described.

- 5 In use the wire 24 is grounded at any suitable point as shown at 26 so that it is thus connected to the grounded terminal of the usual auto battery 28. The other wire 25 is then connected to the conventional ignition switch 29 and this switch 29 is connected to any conventional form of auxiliary switch as designated at 30. The auxiliary switch 30 is then connected to the ungrounded terminal of the battery 28. The 10 arrangement of the wiring is such that both the ignition switch 29 and the switch 30 must be closed in order to complete the circuit to the electromagnet 9. This of course requires that the ignition key (not shown) 15 be placed in the ignition switch 29 and the latter turned to its "on" position before the electromagnet can be operated and so prevents any person other than the driver or owner of the auto from unlocking the gasoline 20 tank. When the switch 29 is turned to its "on" position and the switch 30 is closed the electromagnet 9 is energized and the lock plunger 11 is drawn inward towards the core 15 so that it disengages the catch 16. 25 The coil spring 21 then throws the cap 2 upward somewhat so that the plunger 11 cannot again enter the aperture 18 in the catch 16 when the switch 30 is opened. The cap 2 may then be swung back to present an aperture 30 through which the tank A may be filled. Due to this action of the spring 21 a momentary closing of the switch 30 is sufficient to unlock the cap 2 and the cap will then remain unlocked until depressed against the 35 ring 1 by hand. The arrangement shown 40 may of course be used upon tanks or receptacles of any type and containing any liquid or other material.

While I have herein set forth a certain manner and method of assembling the elements of my invention it is understood that I may vary from the same in minor structural details, so as best to construct a practical device for the purposes intended, not departing 45 from the spirit of the invention and within the scope of the appended claims.

I claim:

1. In a device of the kind described, in combination with a receptacle having an 50 annulus, an attaching ring adapted to fit over the said annulus, means for securing the attaching ring on the annulus, a catch extended from the attaching ring, a cap hinged to the attaching ring, a lock plunger slidably 55 mounted in the cap and spring set to normally engage the said catch, and electromagnetically operated means for disengaging the 60 said lock plunger from the catch.

2. In a device of the kind described, in 65 combination with a receptacle having an

annulus, an attaching ring adapted to fit over the said annulus, means for securing the attaching ring on the annulus, a catch extended from the attaching ring, a cap hinged to the attaching ring, a lock plunger slidably 70 mounted in the cap and spring set to normally engage the said catch, and electromagnetically operated means for disengaging the said lock plunger from the catch, and a spring mounted in the attaching ring and adapted 75 to urge the cap away from the attaching ring a short distance when the lock plunger is disengaged from the catch.

3. In a device of the kind described, in combination with an automobile gasoline tank, ignition switch and battery, a device of the kind described including an attaching ring secured on the tank, a cap hinged on the attaching ring, electromagnetic means for locking and unlocking the said cap on the attaching ring, the said electromagnetic means being connected to the battery through the ignition switch whereby the opening of the cap is under control of the ignition switch.

In testimony whereof I affix my signature. 80
